(57) **CLAIM**

The ornamental design for a floating drink holder for pool, as shown and described.

DESCRIPTION

FIG. 1 is a front, top and right-side perspective view of the floating drink holder for pool showing my new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a rear, bottom and left-side perspective view thereof; and, FIG. 9 is an enlarged view selected from FIG. 1. The broken lines throughout the drawing figures depict portions of the floating drink holder for pool that form no part of the claimed design.
